UNITED STATES PATENT OFFICE.

ADELE WILSON, OF CHICAGO, ILLINOIS.

BABY-JUMPER.

SPECIFICATION forming part of Letters Patent No. 404,241, dated May 28, 1889.

Application filed September 17, 1888. Serial No. 285,612. (No model.)

To all whom it may concern:

Be it known that I, ADÉLE WILSON, of Chicago, in the State of Illinois, have invented certain new and useful Improvements in Baby-Jumpers, of which the following is a specification.

The invention relates to a baby-jumper constructed so as to permit the child to stand upright with its feet upon the floor, or to sit 10 as in a swing; and the objects of my improvements are to provide means for preventing the child from falling out or in any way hurting itself, and to allow it to have the free use of its limbs for exercise. I have attained 15 these objects by the jumper constructed as illustrated in the accompanying drawings, in which—

Figure 1 is a front view of the jumper, with a child represented as standing with its feet 20 upon the floor. Fig. 2 is a similar view with a child represented as sitting in a swing. Fig. 3 shows the entire apparatus without the child.

The invention consists in the parts and combinations hereinafter described, and pointed out in the claim.

I provide a saddle-piece, A, on which the child can sit astride, which is made of cloth and provided with a body-piece, A', which is 30 attached to the front end, a, of the saddle-piece or made integral therewith. The body-piece is of sufficient width to substantially cover the child's body below the arms, and of sufficient length to be wrapped quite or nearly 35 around the body from the front and have its ends connected at the back. The saddle-piece is of sufficient length to be turned up behind and attached at a' to the upper edge of the body-piece, covering the rear ends of 40 the body-piece where they are connected at the back. The saddle and body pieces together, when folded and connected in the manner described, constitute a bag which is open at the top and has a side opening, a², at 45 the bottom on the right and on the left for the lower limbs.

At the top of the body-piece, in front, are placed eyelets or rings c, and at the back similar rings, c', of larger size, through which 50 rings c² on the free end of the saddle-piece may be passed, for the purpose of connecting said free end to the body-piece at the top.

The saddle and body pieces thus constructed and connected are supported by

straps C, which are provided with hooks at 55 their lower ends for connecting in the rings c and c², and have their upper ends connected in a single ring, C', which in turn is connected with a spring, C², by a strap and buckle at C³, so that when the spring is suspended from 60 the ceiling or other support above the height of the jumper above the floor can be readily adjusted.

A hoop, D, is attached to the straps C above the child's head, and spreads them apart so 65 that they will not interfere with the movement of the head.

A lower hoop, D', is suspended from the hoop D by straps D², which are made adjustable vertically by means of buckles at d, so 70 that said hoop may be adjusted to the height of the child's hands.

The jumper is suspended at the proper height, so that the child's feet will just touch the floor, the weight being borne chiefly by 75 the saddle-piece, so that a slight jump, through the aid of the spring above, will send the little one up considerably off the floor, after which it will be let down again.

To use the jumper as a swing, the child is 80 lifted and its knees are placed over the hoop D' in front, allowing the feet to hang down outside said hoop, which is thereby borne down in front and raised behind, so as to take the position shown in Fig. 2.

The connection of the upper ends of the straps D² with the hoop D is made by hook d' passing through holes in said hoop, whereby 85 said straps are made readily detachable at their upper ends, so that the hoop D' is readily detachable from the other part of the apparatus.

What I claim as my invention, and desire to secure by Letters Patent, is—

In a baby-jumper, the combination, with a 95 saddle-piece provided with a body-piece, a suspension-spring, C², suspension-straps C, connecting the saddle-piece and spring, and a spreading-hoop, of a hoop, D', and adjusting-straps D², connecting said hoops, whereby 100 said hoop D' may be adjusted relatively to the body-piece and serve as a rest for the hands or legs of the occupant, as and for the purpose specified.

ADÉLE WILSON.
